UNITED STATES PATENT OFFICE.

FREDERICK F. SCHOLL, OF BOSTON, MASSACHUSETTS, ASSIGNOR TO JOHN HOOD & CO., OF SAME PLACE.

DESIGN FOR A LOCKING-BAR AND HANDLE FOR VULCANIZERS.

SPECIFICATION forming part of Design No. 30,443, dated March 28, 1899.

Application filed February 23, 1899. Serial No. 706,592. Term of patent 14 years.

To all whom it may concern:

Be it known that I, FREDERICK F. SCHOLL, a citizen of the United States, residing at Boston, in the county of Suffolk and State of Massachusetts, have invented and produced a new and original Design for a Combined Locking-Bar and Handle for Vulcanizers, of which the following is a specification, reference being had to the accompanying drawings, forming part thereof.

In the drawings, Figure 1 is a perspective view of a combined locking-bar and handle for vulcanizers, showing the design. Fig. 2 is a plan view of the same.

As shown in the drawings, the leading or material feature of the design consists of the locking-bar A and the handle B, extending at substantially right angles from the said locking-bar intermediate of the latter's ends.

The locking-bar has an elongated form and is swelled at its middle part, as at a, and gradually decreases in size toward its ends a'.

The upper surface of each end is shaped to form an engaging bearing a². Extending through the locking-bar at its central part is 25 a screw-threaded aperture a³.

The shank b of the handle projects from the side of the locking-bar and has a diameter somewhat less than that of the locking-bar. On the outer end of the shank is mounted the 30 handpiece b', and inside of the latter is placed the collar b² on the shank.

Having thus described my invention, what I claim, and desire to secure by Letters Patent, is—

The design for a combined locking-bar and handle for vulcanizers, as herein shown and described.

In testimony whereof I hereunto sign my name in the presence of two witnesses.

FREDERICK F. SCHOLL.
